United States Patent Office

Des. 218,171
Patented July 28, 1970

218,171

TELEPHONE ANSWERING DEVICE

Harold R. Burt, Beaverton, and Ted E. Davids, Portland, Oreg., and Moto Shimano, Los Angeles, Calif., assignors to Ford Industries, Inc., Portland, Oreg., a corporation of Washington

Filed Jan. 23, 1969, Ser. No. 15,460

Term of patent 14 years

Int. Cl. D14—03

U.S. Cl. D26—14

FIG. 4

FIG. 5

FIG. 1 is a perspective view of a telephone answering device showing our new design.

FIG. 2 is a top plan view thereof;

FIG. 3 is a side elevation taken from the left side of FIG. 2;

FIG. 4 is an elevation of the right side of the device in FIG. 2, oriented with the top of the device towards the top of the view; and

FIG. 5 is a rear elevation of the device oriented in the same manner as the view of FIG. 4.

We claim:

The ornamental design for a telephone answering device, as shown.
